HIGH FREQUENCY ANTENNA

Robert F. Lewis, Runnemede, N. J., assignor to
Radio Corporation of America, a corporation
of Delaware

Application October 31, 1938, Serial No. 238,036

6 Claims. (Cl. 250—33)

My invention relates to ultra high frequency antennas, and more particularly to a unitary metallic antenna structure which produces a vertically polarized wave having either a substantially 5 uniform rotating field, or a directional pattern, as desired.

The practice today is to employ a single vertical antenna to radiate vertically polarized high frequency signals. Such antennas exhibit limited 10 gain. It is, therefore, an object of my invention to provide an ultra high frequency antenna having an increased gain.

At present one important use of ultra high frequency transmitters and receivers is in connection with police car communication systems. Dipole antennas and the so-called "turnstile" antenna, which is a highly efficient antenna that has been developed for certain types of ultra high frequency work, are not adaptable to police work, 15 for the reason that they radiate horizontally polarized waves. To properly receive such waves, the receiving antenna must be of a type which is responsive to horizontally polarized waves. Nearly all antennas which are small enough for 20 use on a car and which are responsive to horizontally polarized waves are also highly directive, and consequently are not suited for such use for the reason that automobile antennas must be equally effective in all directions. It is, therefore, a further object of my invention to provide an antenna which is non-directive and which radiates or receives vertically polarized waves.

It is known that there are areas or "dead spots" in which reception is very poor. One method of 25 avoiding dead spots is to transmit a signal simultaneously from more than one point, thus providing more than one path for the radiated wave between the transmitter and receiver. A plurality of antennas at different horizontally spaced 30 points can be energized in a manner that will produce a field which is substantially uniform in all directions, but this condition is only fulfilled when the radiation from all antennas is simultaneously received. It is evident, therefore, that such a 35 system will not prevent fading. It is, therefore, a further object of my invention to reduce dead spots by utilizing a plurality of antenna sections vertically positioned one above the other.

Another disadvantage of the antenna arrays of 40 the prior art, which I propose to overcome in the present invention, is the requirement for insulation between different members of the radiating system. If an antenna tower contains insulated 45 sections, the structure is weakened and its cost is increased. The antenna, according to my

present invention, is made as a unitary metallic structure which does not require any insulating members. It is, therefore, a further object of my invention to provide a unitary antenna structure which is structurally rigid and economical.

The question of feeding antenna arrays must also be considered. In antennas of the prior art which use a plurality of antenna sections having different phase relations, each section must be separately fed, separately tuned, and adjusted 10 for the proper impedance match to the feed lines and for the proper phase. This requires the use of "stand-off" insulators to carry the feed lines, and increases the complexity of the device. It is a further object of my invention, therefore, to 15 provide an ultra high frequency antenna which requires a minimum number of feed lines.

My invention will be better understood from the following description when considered in connection with the accompanying drawing. Its 20 scope is indicated by the appended claims. Similar reference numerals refer to similar parts throughout the several drawings.

Referring to the drawing,

Figure 1 is a schematic diagram to aid in the 25 explanation of this invention;

Figure 2 is a schematic diagram further illustrating the principle of operation of this invention;

Figure 3 illustrates a preferred embodiment of 30 this invention; and

Figure 4 illustrates one method of feeding the antenna shown in Figure 3.

Fig. 1 is a sketch to illustrate the principle of operation of this invention. Three folded over 35 half-wave sections 15, 17 and 19 are connected together at their open ends by two straight half-wave conductors 11 and 13. Each leg of the folded over section is approximately a quarter wave long, and it thus constitutes a resonant phase 40 inverter. At ultra high frequencies, this type of inverter is practical because its overall length is not great. A transmission line 23 is connected to the lower quarter wave inverter 19. The antenna is energized by a transmitter 20 to which the transmission line is connected. Standing waves are set up throughout the entire system by the connection to one inverter. Thus, it is not necessary to run a separate transmission line up to the upper antenna conductor 11.

It is well known that the voltage, or currents, on the opposite legs of a folded half-wave resonant line, at any instant, are of opposite phase. Consequently, there is substantially no radiation from the phase inverting sections 15, 17 and 19. The 55

currents at any instant are indicated by the arrows and are seen to be in phase in the vertical antenna sections 11 and 13 which connect the folded sections.

Referring now to Fig. 2, two sections like that of Fig. 1 have been placed back to back with the closed ends of the quarter wave sections adjoining. The two sections are fed so that the currents in the radiating sections are out of phase. This is accomplished by transposing the connections from the transmission line to one of the sections. The conductor which is connected to the lower arm of the quarter wave section 19 is connected to the upper arm of the quarter wave section 25. Consequently, instantaneous currents in the vertical radiators 11 and 13 are out of phase with the currents in the vertical radiators 12 and 14. As before, radiation from all the horizontal conductors is cancelled out.

In a folded over half-wave line, the mid-point is a maximum current-minimum voltage point, and therefore all such points on the resonant lines 15, 17, 19, 21, 23 and 25 may be grounded. This is also shown in Fig. 2.

Having pointed out the general theory of my invention, a preferred embodiment will now be described. Referring to Fig. 3 a grounded unitary metallic mast antenna 41 is shown which operates in accordance with the principles outlined above. The structure comprises a plurality of sections similar to the one shown and described in Fig. 2. The sections are mounted on the metallic mast 41 and lie in vertical planes which are at right angles. In the preferred embodiment of my invention, there is a total of sixteen vertical half-wave radiating conductors arranged in four groups, each group having four conductors connected in series by the folded over sections. Thus, the complete antenna consists of four groups of vertical radiating antenna elements, each group effectively four half-wave lengths long.

While this antenna may be energized in a number of ways to obtain a number of different uniform or directional field radiation patterns, connections will be described for producing a substantially circular radiation pattern. The connections are best described by reference to Fig. 4, which shows a small section from the lower portion of the structure.

Referring to Fig. 4, the lower folded half-wave sections 19 and 25 are in one plane, while the additional sections 19a and 25a are in a plane at right angles thereto. A transmitter 20 is coupled to a transmission line 27. An adjusting stub section 29 is connected across the line. At a convenient point, the line divides into a pair of lines 31 and 33. One of these lines may be of any convenient length, but the other, 33, for example, is made a quarter wave-length longer, as indicated by the loop 35 marked "90° phase shifter." The lines 31, 33 again divide and terminate respectively at the lower folded half-wave sections 19, 25, 19a and 25a. The lines 31 and 33 are each utilized to energize diagonally positioned pairs of antennas in phase opposition, as shown in Fig. 4. In addition, the currents in adjacent antennas are in quadrature phase relation due to the action of the 90° phase shifter 35. While other connections are possible, by which various directional patterns are obtained, they need not be discussed here, as they are well known to the art.

Each of the folded half-wave sections has a high radio frequency current at the short circuited end. This current may flow through the mast, but it is desirable to connect low resistance con-

ducting elements between the parallel conductors. If the actual length of the horizontal conductors is made somewhat in excess of an exact quarter wave length, some degree of adjustment can be obtained by moving the shorting elements to tune each circuit to resonance.

It was seen in Fig. 2 that the short circuited ends of the quarter wave sections are at the same relative potential end and thus can be connected together and grounded. The mast 41, therefore, need not be insulated from ground. It is also to be noted that the mast 41 passes through an equipotential region with respect to the four antenna elements. As a result any current of a given phase which is induced in the mast by one antenna is opposed by an equal and opposite current which is induced by the equidistant antenna of an opposite phase. The metallic mast, therefore, does not affect the radiation pattern of the antenna.

The efficiency of this antenna is indicated by the fact that it is possible to obtain a gain several times that of a half-wave dipole antenna.

I have thus described an antenna which has high efficiency, radiates a uniform vertically polarized wave, and is free from complex feeding problems. While it has been specifically described as a transmitting antenna, it is evident that it may be used for receiving. Also, more than four vertical sections may be used to increase the gain further. In such a case, the transmission line would not be connected to the lower end of the antenna but, preferably, would be connected in the center of the system.

I claim as my invention:

1. In an antenna of the character described, two pairs of radiating antenna elements disposed in vertical planes intersecting at right angles, each of said elements comprising a plurality of vertical coaxial half-wave conductors, and a plurality of folded half-wave conductors connecting adjacent ends of said radiating elements, said folded half-wave conductors also serving to support said radiating elements.

2. In an antenna of the character described, two pairs of vertical radiating antenna elements disposed in vertical planes intersecting at right angles, each of said elements comprising a plurality of vertical coaxial half-wave conductors, and a plurality of folded half-wave conductors connecting adjacent ends of said radiating elements, said folded half-wave conductors also serving to support said radiating elements.

3. In an antenna of the character described, two pairs of concentric vertical radiating antenna elements disposed in vertical planes intersecting at right angles, each of said elements comprising a plurality of vertical coaxial half-wave conductors, a metallic mast passing through the common center of said radiating elements, and a plurality of folded half-wave conductors supporting and connecting the ends of said plurality of coaxial half-wave conductors to said mast.

4. A unitary metallic antenna comprising a vertical mast, two pairs of vertical radiating antenna elements concentrically disposed about said mast in vertical planes intersecting at right angles at said mast, each of said radiating elements comprising a plurality of half-wave conductors, a plurality of folded half-wave conductors horizontally extending from said mast and connected to and supporting said radiating elements.

5. In an antenna of the character described, a vertical conductive mast for supporting said antenna, two pairs of vertical radiating antenna ele-

ments concentrically disposed about said mast and parallel thereto and lying in vertical planes which intersect at right angles at said mast, each of said radiating elements comprising a plurality of coaxial half-wave conductors, a plurality of folded half-wave conductors horizontally extending from said mast and connected to and supporting said radiating elements, and means for causing in-phase currents to flow in each conductor of 10 said radiating elements.

6. In an antenna of the character described, a vertical conductive mast for supporting said antenna, two pairs of vertical radiating antenna elements concentrically disposed about said mast and 15 parallel thereto and laying in vertical planes

which intersect at right angles at said mast, each of said radiating elements comprising a plurality of coaxial half-wave conductors, a plurality of folded half-wave conductors horizontally extending from said mast and connected to and supporting said radiating elements, means for causing in-phase currents to flow in each conductor of 10 each of said radiating elements, means for causing out of phase currents to flow in oppositely positioned radiating elements of each of said pairs, and means for maintaining a quadrature phase relation between currents in one pair with respect to currents in the other pair. 5
